METAL-CUTTING MACHINE

George J. Pero, Mount Pleasant, Iowa

Application June 30, 1943, Serial No. 492,943

3 Claims. (Cl. 51—98)

This invention relates to new and useful improvements in cutting machines especially adapted for cutting metal, the principal object being to provide a cutting machine which will eliminate long operations with the usual slow progressing hack saw, as well as a reaming out of deep rolled burrs, such as are left by roller type pipe cutters.

Another important object of the invention is to provide a portable cutting machine which can be readily moved about and which is powered for the purpose of eliminating the physical effort necessary in making long cuts in hack saw use.

Other important objects and advantages of the invention will become apparent to the reader of the following description.

In the drawings:

Figure 1 represents a side elevational view of the machine.

Figure 2 is a front elevational view.

Figure 3 is a top plan view.

Figure 4 is an elevational view of the cutting assembly showing the mandrel barrel in section.

Figure 5 is a fragmentary detailed sectional view taken substantially on the line 5—5 of Figure 2.

Figure 6 is a bottom plan view of the motor platform.

Referring to the drawings wherein like numerals designate like parts, it can be seen that numeral 5 generally refers to a frame structure which consists of a pair of parallel bars 6, 6 (see Figure 3) which have extensions at their rear ends that curve upwardly and inwardly as at 7, 7 and terminate in elevated portions that extend forwardly in close parallel relation as at 8, 8 and which are bridged by a member 9 that serves as a handle whereby the machine can be easily carried about.

Bridging and fixed to the forward ends of the portions 8, 8 is a barrel 10 through which a shaft 11 is disposed, the same having bearings 12, 12 in proper relation with respect to the barrel 10. Suitable packing means 13 is provided at the ends of the shaft and a lubricant fitting 14 is provided at the intermediate portion of the barrel 10. The shaft 11 has a threaded extension 15 at one end over which the hub 16 of a cutting wheel or disk 17 is disposed, this hub 16 having a nut 18. The threads of the extension 15 and the hub nut 18 are opposite to that of the rotation of the shaft 11, to the end that the cutting wheel of its own motion cannot unscrew itself.

The other end of the shaft 11 is equipped with a pulley 19 over which a belt 20 is disposed, this

belt 20 extending downwardly to a pulley 21 on the armature shaft 22 of an electric motor 23. The motor 23 has a base 24 which is bolted as at 25 to a platform 26 and this has depending lugs 27 which overlap lugs 28 rising from a cross bar 29 between the portions 6, 6 of the frame 5. Bolts 30 pivotally connect the lugs 27 to the lugs 28. On the cross bar 29 is a teat 31 over which the lowermost convolutions of a compression spring 32 are disposed. A second teat formed by the head of one of the bolts 25 has the uppermost convolutions of the spring 32 disposed thereover. Thus it can be seen, that the spring 32 serves to swing the motor mounting rearwardly and serves as a tightener for the belt 20.

A cross bar 33 is provided at the forward ends of the portions 6, 6 of the frame 5 and on this bar is an elongated tube 34 from which rises a pair of arms 35, 35 and brace members 36 which are interconnected with one of the arms 35 as at 37. The arms 35, 35 support a trough-like table 38, while the brace members 36 support a shorter trough-like table section 39 which is closely spaced with respect to one end of the table 38 so that work can be carried against the cutting wheel 17.

The cutting wheel 17 has a shield supported by a bracket 40, this shield having a lower section 41 and an upper swingable section 42. The lower section has a discharge opening 43 for cuttings, while the forward portion of the upper section 42 is cut away as at 44 to permit work to engage the cutting wheel 17.

While under some circumstances a high speed circular hack saw may be used in place of the wheel 17, a resinoid carborundum cut off wheel has proven very satisfactory.

To limit outward movement of the work supporting table, one or more chains 45 may be interposed between an arm or arms 35 and the cross bar 29.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

- 50 1. A small, readily portable cutting machine comprising a frame consisting of a pair of horizontal spaced side bars having extensions at their rear ends which curve upwardly and inwardly and terminate in elevated horizontal portions that extend forwardly in adjacent spaced relation, a

handle member connecting said elevated portions, a transverse horizontal barrel connecting the forward ends of said elevated portions, a rotary shaft journaled in and extending through said barrel, a cutting disc secured on one end of said shaft, a pulley secured on the other end of said shaft, a transverse member connecting said side bars, a motor mounted on said transverse member and having a pulley on the drive shaft thereof, and a drive belt passing around said pulleys.

2. A small, readily portable cutting machine comprising a frame consisting of a pair of horizontal spaced side bars having extensions at their rear ends which curve upwardly and inwardly and terminate in elevated horizontal portions that extend forwardly in adjacent spaced relation, a handle member connecting said elevated portions, a transverse horizontal barrel connecting the forward ends of said elevated portions, a rotary shaft journaled in and extending through said barrel, a cutting disc secured on one end of said shaft, a pulley secured on the other end of said shaft, a transverse member connecting said side bars, a motor mounted on said transverse member and having a pulley on the drive shaft thereof, and a drive belt passing around said pulleys, a cross bar

connecting the forward ends of said side bars, a tube rotatably fitted on said cross bar, arms rigid with and rising from said tube, and a transverse work rest carried by the upper ends of said arms.

5 3. A small, readily portable cutting machine comprising a frame consisting of a pair of horizontal spaced side bars having extensions at their rear ends which curve upwardly and inwardly and terminate in elevated horizontal portions that 10 extend forwardly in adjacent spaced relation, a handle member connecting said elevated portions, a transverse horizontal barrel connecting the forward ends of said elevated portions, a rotary shaft journaled in and extending through said barrel, 15 a cutting disc secured on one end of said shaft, a pulley secured on the other end of said shaft, a transverse member connecting said side bars, a motor mounted on said transverse member and having a pulley on the drive shaft thereof, and a drive belt passing around said pulleys, and a 20 shield for said cutting disc supported by one of said elevated extension portions, said shield being cut away at the front and having a rearwardly directed cuttings discharge opening at the bottom thereof.

GEORGE J. PERO.
